UNITED STATES PATENT OFFICE.

WILHELM HEINR. AUG. SIEVERTS, OF HAMBURG-UHLENHORST, GERMANY.

APPARATUS FOR FORMING INCANDESCENCE MANTLES FOR GAS-LIGHTS.

SPECIFICATION forming part of Letters Patent No. 621,979, dated March 28, 1899.

Application filed December 2, 1898. Serial No. 698,101. (No model.)

To all whom it may concern:

Be it known that I, WILHELM HEINRICH AUGUST SIEVERTS, teacher, of Hamburg-Uhlenhorst, Germany, have invented certain new and useful Improvements in Apparatus for Forming Incandescent Mantles for Incandescence Gas-Lights; and I do hereby declare that the following is a full, clear, and exact description of the invention.

10 This invention relates to an apparatus for forming incandescent bodies.

The object of this apparatus is in the first place to form a firm and foldless shield or ring at the apex of the incandescent body.

15 The shaping of the incandescent body is effected by suspending the same directly after its having been reduced to ashes from the top of the burner by subsequently placing the burner, together with the incandescent body, 20 upon a disk adapted to rotate around a Bunsen burner, by then igniting the gas traversing the Bunsen burner, and by finally exposing the burning and rotating incandescent body to the action of a suitable jet or blast-furnace passing in inward direction. While 25 the burner, with the incandescent body, is rotating around the Bunsen burner, illuminating-gas is introduced into the said burner at a low pressure. If then the jet or blast flame

30 is caused to act upon the apex in an inward direction, the apex is brought into the form of a solid shield or ring, which prevents the body from yielding as to form a point and so that the folds produced by the contraction 35 of any asbestos thread will disappear. The same method may be utilized in order to cause the lower part of each incandescent mantle to closely join the head of the appertaining burner. Owing to the inwardly-di-

rected and inwardly-acting jet-flame passing 40 against the lower part of the incandescent mantle the latter is intimately applied in an inward direction against the burner-head and becomes softened, so that while exactly

following the outlines of the burner-head it 45 receives corresponding folds.

The apparatus for carrying out the methods is illustrated in the accompanying drawing. The same consists of a Bunsen burner *a*, which is surrounded by a socket *d*, carrying the disk *b*, and having its bottom end constructed in the form of a rope pulley or disk *c*. The bearing for this rope pulley or disk *c* is formed, on the one hand, by a frame *e*, fixed below the table-top *f*, and, on the other hand, by a plate *e'*, located upon the said frame. The Bunsen burner is provided with external screw-threads upon its lower end, these screw-threads serving to secure the burner in the frame *e*. This burner communicates with a gas-feed pipe *g*. The burner *h*, to which the incandescent body *h'* is to be applied, is drawn over the Bunsen burner *a*, so that the burner stands upon the disk *b* and rotates therewith as soon as the rope pulley 65 *c* is set in motion. Instead of this rotation being produced by the rope pulley it may also be obtained by means of toothed wheel-gearings. The shaping of the incandescent body 70 is effected during the rotation of the burning incandescent body around its Bunsen burner under the action of an inwardly-directed jet or blast flame.

Having now described and ascertained my said invention and in what manner the same 75 is to be performed, I declare what I claim is—

In combination, a Bunsen burner, a disk surrounding the same, and means for rotating the disk about the Bunsen burner, the said disk being arranged to receive the burner 80 with the mantle, substantially as described.

In witness whereof I have hereunto set my hand in presence of two witnesses.

WILHELM HEINR. AUG. SIEVERTS.
